DOUBLE PANE WINDOW

Richard L. Horstman and Floyd L. Oelfke,
Kansas City, Mo.

Application July 14, 1947, Serial No. 760,867

2 Claims. (Cl. 20—56.5)

1

This invention relates to window construction, the primary aim being to provide a window having a pair of spaced apart panes provided with novel framework for holding the panes and adapted to permit easy and quick assembling.

The most important object of this invention is the provision of a double pane window having a channel-frame for receiving the panes and a secondary frame fittable between the panes for holding the same in spaced apart relationship and against the aforesaid channel-like frame.

Another important object of this invention is to provide double pane windows of the aforesaid character having strips of resilient material throughout all of the outermost marginal edges of the panes and interposed between said panes and the channel-like frame for presenting a positive seal when the secondary frame is moved into position.

Another important object of this invention lies in the interlocking means and weather stripping particularly adaptable for use in double hung windows using the window construction forming the subject matter of this invention.

Many minor objects relating particularly to details of construction will be made clear during the course of the following specification, reference being had to the accompanying drawing, wherein:

Fig. 1 is a side elevational view of a pair of double pane windows made in accordance with our present invention.

Fig. 2 is a cross sectional view taken on line II—II of Fig. 1.

Fig. 3 is a fragmentary detailed cross sectional view taken on line III—III of Fig. 1; and

Fig. 4 is a stretched-out perspective view showing the frame sections per se for the double pane window.

The window construction about to be described includes a pair of frames broadly designated by the numerals 10 and 12 respectively. The frame section 10 includes a pair of side members 14 of identical character, a bottom 16 and a top 18. These members 14, 16 and 18 of the frame section 10 are U-shaped in cross section to present a continuous inturned channel when the sections are assembled. The bight portion 20 of the bottom 16, extends beyond the legs 22 of bottom 16 at each end thereof for receiving the side members 14. In other words, when assembled, the legs 22 of bottom 16 are interposed between the legs 24 of the side members 14. When so assembled, the side members 14 are welded or otherwise fused together not only along the ends

of the legs 22 but along the marginal edges of bight portion 20 in contacting relationship with the lowermost ends of the members 14. The top 18 is made substantially the same as the bottom 16 with the exception that the bight thereof has an elongated slot 26 formed therein. The downturned legs of this top 18 fit between the legs 24 of members 14 in the same manner as above described with respect to the bottom 16 and this top 18 is welded together with the members 14 in the same manner.

Each of the side members 14 is provided with a longitudinal inturned channel 28, as clearly illustrated in Figs. 3 and 4, to receive the conventional cords when the window construction is formed in a double hung window as illustrated in Figs. 1 and 2. The secondary frame 12 is formed from a pair of side members 30 and a top and bottom 32 and 34 respectively. These portions 30, 32 and 34 of frame 12 are polygonal in cross section, as shown in Figs. 2 and 3 and preferably hollow to the end that the frame 12 is relatively light. It is understood that in lieu of the form of members 30, 32 and 34 as shown, these members may be U-shaped in cross section if desired to further add to lightness.

Extending throughout the length and disposed upon the innermost faces of all of the legs of members 14, 16 and 18 of the frame 10, are strips of resilient material 36. This material 36 is preferably made from sponge-rubber, although any material having like characteristics may be used. These strips of material 36 are thus disposed in spaced apart opposed relationship within the individual members forming frame section 10 and are secured to the bights thereof by a suitable adhesive, if desired. As shown in Fig. 3, the width of resilient strips 36 is substantially the same as the width of the bight portions of the top and bottom 18 and 16 respectively of section 10, but in the case of the side members 14, the resilient strips 36 are somewhat narrower to provide sufficient clearance for the sash cord notches 28. When the frame section 10 is completely assembled and the resilient strips 36 therefore are sealed in place, a pair of panes 38 are inserted within frame section 10 through slot 26 formed in the top 18 thereof. If desired, a coating of adhesive may be applied between the innermost faces of all of the strips 36 and the proximal outermost edges of the panes 38. After these panes 38 are moved into place, the frame section 12 is inserted between panes 38 through the slot 26. The width of the frame 12 should be such as to wedge tightly between the panes

2

38 and to slightly compress the resilient strips 36. Such tight fit of the frame section 12 between the panes 38 will effectively hold the same in place as well as to hold the panes 38 against displacement. The space between the panes 38 will present effective insulation and to further this feature, it is contemplated that a suitable valve be provided in the frame member 12 to completely evacuate the space between panes 38.

As illustrated in Fig. 2, when windows are made as above described utilizing a polygonal frame 10, the bottom 16 thereof will not conform to the usual type of sloping window sill 40. To present an effective weather strip seal, a resilient member 42 is welded to the lowermost face of bight 20 of bottom 16. This strip 42 extends the entire length of the bottom 16 and is looped upon itself as is clearly shown in cross section in Fig. 2.

When the lowermost of the two double hung windows is moved to the closed position, this strip 42 will strike the sloping sill 40 and the looped portion will be slightly compressed to present a virtually air-tight seal. By the same token, when this window construction is used in the conventional double hung window frame, the two windows will be in spaced apart relationship because of the dividing strip 44 of the frame 46. An interlocking seal is formed between the two windows by the use of a pair of members 48 and 50 respectively. These members 48 and 50 are secured in any suitable manner to the proximal faces of the frames 10 of each of the double hung windows. In other words, the member 48 is preferably attached to the bottom 16 of the uppermost frame 10 while the member 50 is affixed to the top member 18 of the lowermost frame. The member 48 has a laterally extending portion 52 projecting toward the member 50 and this portion 52 has its end up-turned as at 54. The member 50, however, is L-shaped and is welded or otherwise affixed to the uppermost face of the top member 18. One leg of this member 50 is slightly inclined as at 56 and the lowermost free edge thereof is disposed to receive the looped edge 54 of the member 48 as shown in Fig. 2. These members 48 and 50 extend the entire length of the respective windows and when the latter are in the closed position as illustrated in Fig. 2, a virtually air-tight interlocking seal is presented between the members 48 and 50. The two double hung windows may be easily opened and closed and when moved to the closed position, these members 48 and 50 will automatically interlock.

A strip 58 is also secured to the top 18 of the upper-most window as shown in Fig. 2. This strip 58 extends the entire length of the top 18 of the frame 12 and is made from any suitable resilient material. Securement to top 18 of strip 58 may be by welding as at 60 or any other desired manner, and this strip 58 extends at an angle upwardly from point of fastening 60 when the window is open. As the window is closed against the

framework 46, a tight seal is presented by the flexing of strip 58 and wedging of the same between top 18 and frame 46.

It is clear from the foregoing that the window construction chosen for illustration will be extremely durable, relatively light and attractive in appearance. The panes 38 may be easily replaced when broken, by the simple expedient of removing the frame 12. Under no circumstances will the panes 38 become loose within the frame 10 and an air-tight seal is presented that will not easily establish leaks.

While only one modification of our double pane window has been illustrated and described, it is manifest that many changes and modifications may be made particularly with respect to details of construction without departing from the spirit of the invention or scope of the appended claims.

Having thus described the invention, what is claimed as new and desired to be secured by Letters Patent is:

1. A window comprising a pair of spaced panes; a continuous frame circumscribing the peripheries of said panes, said frame being U-shaped in cross-section presenting spaced legs overlapping proximal outermost marginal edges of said panes, said frame having an opening formed therein; and a continuous, rigid secondary frame adapted for insertion into said opening between the panes for holding the latter spaced apart, said secondary frame having a peripheral part for closing said opening when the secondary frame is between the panes.

2. A window comprising a pair of spaced panes; a continuous frame circumscribing the peripheries of said panes, said frame being U-shaped in cross-section presenting spaced legs overlapping proximal outermost marginal edges of said panes, said frame having an opening formed therein; and a continuous, rigid secondary frame adapted for insertion into said opening between the panes for holding the latter spaced apart, said secondary frame having a peripheral part for closing said opening when the secondary frame is between the panes, the remainder of the periphery of said secondary frame, exclusive of said part, bearing against the inner faces of proximal bight portion of the U-shaped frame.
